UNITED STATES PATENT OFFICE.

SAMUEL EMIL WEILL, OF LONDON, ENGLAND.

MACHINE FOR POLISHING SHEET MATERIAL.

Application filed March 6, 1924, Serial No. 697,204, and in Great Britain November 14, 1923.

This invention comprises an improvement in or a modification of the polishing machine described in the specification of my former British Patent No. 205,313, employing a counterbalanced polishing mop, and has for its object to simplify the construction and thereby lessen the cost of manufacture of the said machine.

In the accompanying drawings—

10 Figure 1 is a side elevation of a machine for polishing sheet material, constructed in accordance with the invention.

Figure 2 is a sectional plan thereof.

15 Figure 3 is a view of the machine looking from the front end.

Figs. 4 to 7 inclusive are detail views of the mounting for the gripping bars.

In the said specification two pairs of contacting rollers are described for feeding the sheet material beneath the polishing mop, one in front and one at the rear of the said mop, and the main object of the present invention is to dispense with the said rollers.

According to my present invention I substitute for the said feed-rollers a feed device or devices acting to receive and grip or hold the sheet or sheets to be polished and to travel along the table of the machine beneath the polishing mop and then to release the polished sheet or sheets, the feed device or devices then being returned to the receiving or gripping position.

In a suitable arrangement for carrying out the invention I form each gripping device of a pair of bars extending transversely of the machine table, between which bars the plate to be polished is gripped along one edge, the lower bar being rebated to receive the edge of the said plate and the upper bar fitting into the said rebate and being pressed therein by a spring at each end. The opposed or gripping faces of the bars are advantageously roughened. The pairs of bars are mounted on a pair of endless chains passing around rings of sprocket teeth on rollers mounted in bearings at the ends of the table, one of which rollers is rotated to drive the chains to move the gripping bars along the table by sprocket mechanism and gearing driven by the main or driving shaft of the machine.

To separate the upper bar from the lower bar of each pair when receiving or releasing a piece of sheet material, a pair of bell-crank levers is arranged designed to bear at one end beneath the respective ends of the

said upper bar, guide or camrails being provided on the machine against or beneath which the other ends of the bell-crank levers ride, so that the said levers are moved to effect the said separation.

To prevent the polishing mop being fouled by the gripping devices when passing thereunder, extensions are provided on the pivoted frame carrying the said mop, with which a fitting or extension on each of the devices is designed to come into contact, thereby lifting the said frame and consequently the mop.

I also provide means for adjusting the 70 mop to any desired position relatively to the work according to the pressure to be exerted thereon by the said mop, instead of depending on the adjustment of the counterbalance weights. For this purpose, I provide a sliding or adjustable stop which limits the movement of the mop towards the machine table, this stop being arranged in the path of the controlling hand-lever which is advantageously connected to the 75 lever on the shaft carrying the counterbalance by an adjustable link comprising a nut pivoted to the said lever and a screwed rod controlled by a hand-wheel engaging the said nut and carried in a bearing pivoted to the said hand-lever.

80 *a* is the table of the machine supported by side frames *b*, *b* and front legs *c*, *c*. *d* is the polishing mop arranged above the table *a* and *e* is the roller arranged in the table below the said mop and serving to support the sheet material under the action of the mop, the upper portion of the periphery of the said roller being located in the slot *f* in the table *a*. *g* is the lever-frame fulcrumed at one end on the shaft *h* carried by the frames *b* and carrying in bearings *i*, at its outer end, the shaft *j* on which the mop *d* is fixed and by which it is rotated. In addition to its movement of rotation, the 85 mop *d* is capable of being reciprocated longitudinally by means of the bell-crank lever *k*, one arm of which engages the grooved collar *l* on the shaft *j*, whilst the other arm thereof is connected by the rod *m* with the crank *n* rotated by gear-wheels *n¹*, *n²*, the latter of which is carried by the sleeve or hollow main shaft *o* mounted on an extension of the shaft *h* and rotated by the pulley 90 *p*.

100 *p* is the counterbalance for the mop *d*, whereby the latter is maintained in a semi-

floating condition, which counterbalance is in the form of a weight adjustably carried on the lever p^1 fulcrumed in the frame sides b, b by the cross shaft p^2 , the latter having the two levers p^3 thereon connected by the links q, q to the frame g . By varying the position of the counterbalance p on the lever p^1 , the pressure of the mop upon the material to be polished can be varied. r is the hand-lever for raising the mop clear of the table, when moved in the direction of the arrow 1, Figure 1, the said lever being fulcrumed at r^1 to one of the frame sides b and connected by a link r^2 to a lever r^3 on the shaft p^2 .

s is the belt pulley for rotating, by means of the belt s^1 , the shaft j carrying the mop d and t is the shaft carrying the said pulley, and which shaft is arranged in the bearing t^1 in the lever-frame g in axial alignment with the said shaft j . u is the clutch connecting the pulley s to the shaft j so that the latter can be reciprocated longitudinally in its bearings without corresponding movement of the said pulley, u^1, u^2 being pins on the pulley s which slide in holes in the clutch u when the shaft j is reciprocated and maintain the driving connection between the said pulley and shaft.

v, v^1 are the guide pulleys around which the belt s^1 passes to maintain the said belt taut, notwithstanding movements of the lever-frame g around its fulcrum, these two pulleys being arranged on the shafts v^2 in bearings on the frame g on opposite sides of the shaft h and equidistant therefrom on a line passing through the said fulcrum and at right angles to the axial line of the said frame g , the said belt s^1 passing around a driving pulley above the machine and not shown, around the pulley v , around the pulleys s and v^1 and around the guide pulley v^3 on the pivot v^4 on one of the frame sides b back to the said driving pulley.

w, w^1 are the pair of bars forming each of the gripping devices for the sheets or plates A to be polished, and extending transversely of the table a , the one or front edge of such a sheet or plate being placed between and gripped by the said bars and moved backwards from the front of the table beneath the mop d . The lower bar w^1 is rebated, as shown in Figure 6, to receive the edges of the sheet or plate A, the upper bar w fitting into the rebate on to the top of the sheet or plate A, and being pressed therein at each end by the spring w^5 carried by a fitting w^6 on each end of the bar w . w^1, w^2, w^3 are the pair of endless chains on which the pairs of bars w, w^1 are mounted and which are directly attached to the fittings w^6, w^7, w^8 . w^5 are the pins of sprocket teeth in mesh with the chains w^4 and carried on the rollers w^6 and w^7 mounted in bearings w^8 at the front and back ends of the machine, respectively. w is

a sprocket wheel on one end of the roller w^7 driven by a sprocket chain w^1 from a sprocket wheel w^2 pivoted on a fixed stud or shaft w^3 and attached to a spur wheel w^4 in mesh with the wheel w^2 . w^5, w^6 are the bell-crank levers having their inner ends bearing beneath the respective ends of the upper gripping bar w and pivoted to the fittings w^6 and which are moved to raise the said bar against the pressure of the springs w^3 when receiving or releasing the piece of sheet material A. w^6, w^7 are the guide or cam rails on the table a beneath which rails the outer ends of the bell-crank levers w^5 pass in their passage along the said table and are depressed thereby so as to lift the gripping bar w , a pair of the said rails being arranged at the front and at the back of the machine, those at the front allowing of the insertion of a sheet to be polished between the gripping bars w, w^1 and the pair at the back of the machine effecting the release of the sheet when polished, the said sheet being either removed by hand or by gravity.

y, y^1 are the extensions on the mop carrying frame g with which rollers y^1, y^2 on the fittings w^9 of the gripping devices w, w^1 are designed to come into contact to lift the said frame and consequently the mop d to prevent the latter being fouled by the said gripping device when passing under the mop.

z is the adjustable stop for determining the position of the mop d relatively to the work according to the pressure to be exerted thereupon by the said mop, the said stop being in the form of a bar having a slot z^1 through which pass a pair of set-screws z^2, z^3 screwing into one of the frame sides b and serving to secure the said bar after adjustment longitudinally. The link r^2 connecting the hand-lever r to the lever r^3 is in the form of a screwed rod engaging at one end the nut r^4 pivoted to the said lever and at the other end rotating in the bearing r^5 pivoted to the said hand-lever, endwise movement of the rod r^2 in the bearing being prevented by the collars r^6, r^7 . After roughly setting the stop z a fine adjustment of the working position of the mop can be effected by rotating the rod R^2 . Or, the stop z need not be adjustable, the required adjustment of the mop relatively to the work being effected wholly by the rod r^2 .

Claims:—

1. In a machine for polishing sheet material, the combination with a supporting table for supporting the sheets while they are being polished, endless chains movable along the machine table, pairs of bars each having a length greater than the transverse width of the sheets to be polished, carried by said chains, said bars being adapted to grip the sheets between them throughout the length of said bars, a horizontally movable polishing mop located above the table for

engaging the sheets supported thereby, and means for causing the bars carried by said chains to automatically grip and release the said sheets.

- 5 2. A machine for polishing sheet material comprising a table for supporting the said material, a rotary polishing mop arranged above the table and movable towards and away from the latter, a lever frame carrying 10 the mop and provided with a variable counterbalance, a supporting roller arranged beneath the mop in a slot in the table, endless chains movable along the table, bars carried by the chains for gripping the sheet material 15 between them and moving it beneath the mop and means for causing the said bars automatically to grip and release the said material during the movement of the chains.
3. In a machine for polishing sheet material, the combination with a supporting 20 table for supporting the sheets while they are being polished, endless chains movable along the machine table, pairs of bars each having a length greater than the transverse 25 width of the sheets to be polished carried by said chains, said bars being adapted to grip the sheets between them throughout the length of said bars, a horizontally movable polishing mop located above the table for 30 engaging the sheets supported thereby, springs for holding said bars in gripping engagement, levers for separating said bars against the pressure of said springs, and fixed guide rails adjacent to the edges of the 35 table for engaging said levers to effect the

opening and closing of said bars during their travel along the machine table.

4. In a polishing machine as claimed in claim 2, wherein means are provided for automatically lifting the mop clear of each 40 gripping device, as it passes thereunder.

5. In a polishing machine as claimed in claim 2, means for lifting the mop clear of the gripping device, or each such device, comprising an extension on the pivoted lever 45 frame carrying the mop and an extension or fitting on the said gripping device co-acting with the extension on the lever frame.

6. In a polishing machine as claimed in claim 2, means for adjusting the mop relatively to the work comprising a stop on the machine arranged in the path of a hand-lever for raising the mop and an adjustable connection between the said hand-lever and the mop carrying mechanism. 50

7. In a machine for polishing sheet material, the combination with a table, a rotary polishing mop mounted thereon, endless chains movable along the table, transversely disposed pairs of gripping bars carried by 60 said chains, springs holding said bars in gripping relation, bell-crank carried by said chains at each end of each pair of gripping bars and having one end interposed between said bars, and stationary cam rails 65 supported adjacent to the travel of said chains for engaging the other end of adjacent bell-cranks to effect the separation of said gripping bars.
